UNITED STATES PATENT OFFICE.

MAX HELLER, OF BERLIN-CHARLOTTENBURG, GERMANY.

METAL-SCOURING AND UNGREASING DEVICE.

Application filed September 14, 1920. Serial No. 410,328.

(GRANTED UNDER THE PROVISIONS OF THE ACT OF MARCH 3, 1921, 41 STAT. L., 1818.)

To all whom it may concern:

Be it known that I, MAX HELLER, manufacturer, a citizen of Czechoslovakia, and residing at Berlin-Charlottenburg, Kantstr. 122, Germany, have invented certain new and useful Improvements in or Relating to Metal Scouring and Ungreasing Devices, for which I have filed application in Germany, Sept. 12, 1919, Serial No. H. 78,323, Patent No. 345,720, of which the following is a specification.

My invention relates to a metal-scouring and ungreasing device. In accordance with my invention the parts to be scoured are treated, in a closed scouring-tank or the like, with hot liquids such as trichlorethylen (C_2HCl_3) benzine, benzol, tetrachloride of carbon (CCl_4) etc. The scouring liquid is conducted from a collector into the scouring-tank and is again drawn off after the scouring operation has been finished. Now, in order to secure a thorough drying of the articles so scoured, and in order to prevent an escape and therewith a loss of the vapours developed when heating the scouring-liquid on opening the scouring-tank for the purpose of taking out the articles scoured, the said scouring-tank is provided with a cooling-device adapted to cool the said tank or a part, preferably the bottom thereof, after the scouring operation has terminated. The result of this arrangement will be that any vapours which may happen to be still present in the tank will settle on the part of the tank cooled, while any moisture still existing on the scoured articles will evaporate for the reason that these articles, being still hot, will possess a higher temperature than the part of the tank which has been cooled, so that the vapours developed in consequence will likewise deposit themselves on the said part in the form of a liquid. It will be noted that by proceeding in this manner, the loss of liquid will be reduced to a minimum and that more-over the articles when taken out of the tank will be perfectly dry. The scouring liquid, which in the course of its application has been saturated with fats and mechanical impurities, may be recovered in a state of entire purity by means of distillation, while the fatty impure matters constitute the re-

sidues remaining behind in the alembic or still.

The washing tanks are preferably separated into two parts by means of a partition, the upper part serving to accommodate the articles to be scoured, while the lower part is destined to secure a good running off of the scouring-liquid from the articles scoured, as also to receive the vapours which will settle across the whole area of the cooled bottom. The heating of the scouring-liquid may be effected by the direct heating of the scouring-tank. In order to avoid, however, the possibility of the scouring-liquid being overheated and consequently, the boiling over thereof, and furthermore to enable the bottom of the scouring-tank to be quickly cooled after the scouring-liquid has run off, it will be found more practiceable to heat the collector instead of the scouring-tank. This will result in the scouring-liquid being already heated up to the required degree when it is being introduced from the collector into the scouring-tank.

An additional feature of my invention resides in the fact that the scouring-liquid is arranged to continuously flow into the scouring-tank, so that the quantity of liquid cooling off on the metal to be scoured is immediately replaced by a fresh, hot supply. For the purpose, moreover, of keeping the liquid in constant circulation, it is introduced into the tank in a tangential direction.

In the event of the articles to be scoured being not only oily or greasy, but being also covered with dust, in particular such resulting from grinding, then obviously a simple washing of said articles in the liquid will frequently not effect a satisfactory cleaning thereof. In such cases, it will be found expedient in accordance with this invention to movably arrange the interior parts of the scouring-tank, namely the sieves or frames containing the articles to be secured, and this in such wise that they may be put in rotation either by hand or by mechanical means relatively to the scouring-liquid; the current thus provoked is sufficient to reliably remove even dust particles adhering to the metal surfaces.

The scouring and ungreasing of hollow bodies, such as coffee-cans, tea-pots, and the

like, generally proves very difficult, for the reason that the said articles can never be so disposed along the bottom of the device that when the scouring-liquid is introduced into the tank it will completely fill the said articles, and that the scouring-liquid does not entirely run out again therefrom when it is being discharged. It is an additional object of my invention to obviate this draw-
back by the provision of an air-vent pipe adapted to establish a communication between the interior of the hollow vessel to be scoured and the air of the atmosphere outside the scouring-tank or also present above the scouring-liquid while this latter is being introduced into said tank.

A further means to secure a satisfactory cleansing of such said hollow bodies consists in the bottoms on which these bodies are placed in the tank being so arranged as to allow of their being rocked, whereby the hollow articles contained thereon may be so turned after the scouring operation has been terminated that all the scouring-liquid will come to flow out. In this connection the said bottoms are so arranged that during the filling in of the scouring-liquid they will assume such a position as to ensure any hollow vessels lodged in the tank to be completely filled with the said liquid so that they will contain no vacant air-spaces. To this end the bottom may be rocked by any approved means; the method most suitable which will require no parts of a gearing to project through the wall portions of the device, will be the one in which the said movement is effected by the intervention of a float.

Where hollow bodies require to be treated in the case of which it will not matter whether the outer surface thereof be slightly damaged or not, i. e., if bodies which, for example are to be subsequently, tin-coated, japanned or enamelled, it will prove more expedient to place them in a drum suspended in the scouring tank which is put in rotation after the scouring-liquid has been introduced into the tank and again after this latter has been drawn off on the conclusion of the scouring operation in order to first completely submerge the articles to be scoured in the said liquid and then just as completely to ensure the flowing off thereof.

In the case of small works, where only a comparatively slight number of parts are required to be scoured, or in cases where only a limited space is available so that large size installations cannot be made use of, a special form of construction will preferably be employed in the case of which the scouring-tank and the collector are so arranged as to be able to execute a movement in the vertical direction relatively to each other, in order to enable the scouring-liquid to flow from the one receptacle into the other without the intervention of a pump, or the like.

Several embodiments of the subject matter of my invention are shown by way of example in the drawings annexed to this specification and forming a part thereof, and in which

Fig. 1 is a diagrammatic view of the one embodiment of my invention,

Fig. 2 a section through the scouring-tank according to line 2—2 of Fig. 1,

Fig. 3 is a view partly in vertical section 75 of a modified form of construction thereof,

Fig. 4 a view partly in vertical section of a second modification of a scouring tank suitable for scouring hollow vessels,

Fig. 5 a cross-section through the structure according to line 5—5 of Fig. 4,

Fig. 10 is a sectional view according to line 10—10 of Fig. 9,

Fig. 11 a view partly in vertical section of an installation suitable for small works 95 or where the space available is confined, and

Figs. 12 and 13 views illustrating two additional means for setting the collector according to the construction shown in Fig. 11 in motion.

Referring to the drawings. In Fig. 1 the reference numeral 1 denotes a collector or receiver for the scouring-liquid which may be of any appropriate kind. Below the collector there is arranged a space 2 in which is provided a heating device 3. The scouring-liquid is conducted from the collector by means of a pump 4, operated by a lever 5, through a pipe 7 controlled by a valve 6 into the scouring-tank 8. The said liquid rises in the scouring-tank and in so doing scours the articles or vessels contained therein, and after having risen to a sufficient extent returns through the overflow branch 9 into the collector 1.

The scouring operation having terminated, the scouring tank is drained by means of a pipe 21 adapted to be closed by a valve 10, the liquid thus drawn off flowing back into the collector. Above the collector there is arranged a condenser receiver 11. A pipe 12 extending from the scouring-tank serves to conduct the vapours developed in said tank into this receiver 11. A pipe 13 controlled by a valve 14 is provided for the purpose of conducting the liquid condensed in the receiver 11 back into the collector.

The repeated utilization of the liquid contained in the collector 1 gradually causes said liquid to be filled with grease and other impurities. For the purpose of removing 130

these said impurities the liquid is, after opening the valve 15 and closing the valve 6, pumped by the pump 4 into a still or alembic 16 and there distilled. The purified vapours thereupon ascend through the pipe 22 into the condenser-receiver 11, where they are condensed and then flow back, in the manner aforesaid, into the collector 1, while the grease and other impurities remain behind in the still and are subsequently drawn off in turn by means of a drain cock, not shown in the drawing.

The bottom, 17 of the scouring tank is preferably constructed so as to constitute a double-bottom, while being at the same time connected to a cooling-water supply pipe 18. As soon as the scouring liquid has been drawn off at the end of the scouring operation, the bottom 17 is thoroughly cooled by the opening of cooling-water supply pipe, as a result the portions of the scouring-liquid still present on the hot surfaces of the articles scoured evaporate quickly, and the vapours which fail to pass off through the pipe 12 rapidly settle on the bottom 17 now cooled as aforesaid, so that the articles scoured, dry rapidly and may be removed from the scouring-tank in a perfectly dry state, while no loss of scouring-liquid will have taken place.

The scouring-tank 8 may be divided by means of a false bottom 20 into two parts, and in addition may be provided with a detachable cover 19 to facilitate the putting in and taking out of the articles to be scoured. These latter are placed on the false bottom 20 through which the scouring liquid can pass. The pipe 7 terminates underneath the bottom 20 and this, as disclosed by Fig. 2 in a tangential direction, so that the liquid will encounter a very small resistance as it flows into the tank and therefore is directly put in circulation. The tank gradually fills, the liquid in due course covering the articles or vessels to be scoured until it has finally mounted so high that it comes to attain the overflow branch 9 through which it eventually flows back into the collector 1. The advantages secured by this arrangement are that fresh, hot scouring liquid is continuously pumped out of the collector into the scouring tank and brought into intimate contact with the articles to be scoured; that the said liquid is kept in constant circulation in the tank, and, that from the very outset there is produced a strong motion even before the scouring-liquid has reached the articles to be scoured. If, for instance, the pipe 7 were arranged above the false bottom 20, then the liquid in entering would encounter the metal articles carried by said bottom and would thus be prevented from properly circulating. In addition, since the space beneath the false bottom 20 would still be unoccupied, the liquid would initially fall on entering the tank, whereby its circulation would be impeded. On the contrary, by entering from below the false bottom 20, the liquid meets with no obstacle whatsoever and may at once start circulating.

In the event of the articles to be scoured being not only greasy or oily, but in addition being covered with dust, in particular such as is caused by grinding, then it will be found preferable to employ a scouring-tank constructed on the lines laid down by Fig. 3. In this modified form of construction there is arranged on the bottom of the scouring-tank a foot-step bearing 23 within which a pin 24 is adapted to move. This pin 24 is fixed to a perforated disk or a cross or star-shaped member 25, provided with upwardly extending guide rods 26 or the like. The members 25, 26 practically form a frame 85 into which circular sieves 27 containing the articles to be scoured, may be inserted from above. These sieves are constructed in the customary manner, and are provided with handles, abutments, or the like 28 arranged in such a manner that the sieve, which happens to be on the top for the time being will come to rest on the handles or the like 28 of the sieve immediately underneath, and will thus be kept at a proper distance therefrom. After the sieves 27 have been inserted, there is placed a perforate plate or else a star or cross-shaped cover 29, provided with a pin 30 projecting beyond the cover 19 of the scouring tank. This last-named pin is suitably packed in any appropriate manner to minimize any possible loss of the scouring-liquid. In this connection it will be found expedient to arrange on the one side of the cover 19 a funnel-shaped enlargement 31 to enable the said cover to be easily fitted upon the pin 30. This latter is provided at its unsupported end with a square-shaped head 32, or the like, adapted to accommodate a hand or crank 33.

By suitably rotating this crank, the entire frame along with the sieves contained therein may be revolved whereby a powerful motion is provoked relatively to the liquid. The crank 33 may, as preferred, be either constantly turned in one direction, or it may be alternately rocked to and fro, or else, after the liquid has been put in rotation, it may be suddenly stopped, and the like. Instead of turning the crank by hand, it may of course, also be rotated by mechanical means, and in the like way. Instead of a rotatory motion, a vertical motion in the axial direction, or a combination of both motions, such as, say a helical motion, may be employed. The point of essential importance for the invention is only that by reason of movable arrangement of the frame supporting the articles to be scoured there shall always be provoked a strong current inter-

mediate the said articles and the scouring liquid.

A feature characterizing the invention resides in the fact of the scouring liquid not being heated in the scouring-tank, but in the collector. In those cases, however, where the liquid is heated by means of steam or steam coils, the heating contrivance may, of course, also be arranged in the scouring-tank proper, because in such a contingency there will be no liability of the bottom of the tank being heated to any excessive degree.

The devices disclosed in Figs. 4 to 10 serve for the scouring and ungreasing of hollow vessels or the like. In connection herewith the scouring tank 8 is provided with a special air-vent piping in order to draw off the air from the said hollow vessels. To this end there may be provided, as shown in Figs. 4 and 5, say, for example, annular pipes 34, 35, 36, etc., which are preferably disposed concentrically to each other and which may be interconnected to form a system by aid of connection pipes 37. The whole system is lodged at an incline, there being provided a discharge pipe 39 at the lowermost point thereof extending through the scouring tank to the exterior and there terminating in a collector 40. This latter communicates with the discharge pipe 38 by intervention of a pipe adapted for its part to be shut by a cock 41. To the uppermost point of the system of concentrically disposed pipes there is connected a pipe 42 extending vertically upwards which either terminates within the scouring tank above the overflow pipe 9, or else may also be conducted out of the tank into the exterior. On the pipes 34, 35, 36 are mounted at suitable distances apart pipes 43 extending vertically upward which terminate at the same height and on which the articles 44 to be scoured are placed upside down. If now the scouring liquid be admitted through the pipe 7, then it will gradually ascend within the scouring-tank. By these means air comes to be imprisoned in the articles or vessels 44. As the liquid continues to mount, the air thus imprisoned may be drawn off by the pipe 43 terminating within the vessels 44 and conducted downward into the corresponding annular pipe, and thence through pipe 42 so that now the liquid may rise in the said vessel as far as the bottom thereof, whereby a thorough scouring is effected.

Again, if it be desired to scour broad articles, such, for instance, as bread-baskets 48, or the like, then it will be found expedient to fix supports 45 on the pipes 43 by means of clamps, or the like, which supports may be of wire, or the like, and which will serve to maintain the said articles in a proper horizontal position.

In a modified form of execution the rigid pipes 43 are replaced by flexible hose or tubes 46 connected to the annular pipes 34, 35, 36 at suitable points thereof, stationary standards 47 being erected on the perforated bottom 20 of the scouring tank, on the upper ends of which there is arranged a suitable contrivance for scouring the hose or tubes 46, say, for example, a hook or a double guide, or the like. It is understood, that the said standards 47 must all be of equal height. The advantage of this arrangement over and above that of rigidly fixed pipes 43, resides in the fact that the standards 47 may be disposed within the scouring tank according to requirement and that they consequently may serve to scour hollow bodies of divers sizes and utilizing the space available to best advantage.

As soon as the scouring liquid has mounted beyond the articles to be scoured, the pipes 43 and 47 respectively, and therewith also the annular pipes, begin to be filled with the liquid, as a result, in order to get the tank ready for a fresh scouring operation, the liquid must be primarily drawn off again from the said pipes. This is done after the scouring liquid has been allowed to run off in the customary manner, by opening the cock 41 so that the liquid contained in the aforementioned pipes may now flow into the discharge pipe 38. The collector 40 is arranged for the purpose of receiving any remains of the liquid which may still happen to be in the pipes, as also such liquids which may have collected while the tank was being filled say, for instance, by splurting, by condensing of any vapours present, or the like.

This arrangement embodies the advantage that the interior of the vessel to be scoured is bound to be thoroughly cleansed, and this without the said vessel being with its outer surface brought into any contact whatsoever with any sieves or the like, whereby the possibility of the exterior of the vessel being in any way scratched is entirely obviated. It will be found that by means of this modified arrangement, vessels may be satisfactorily scoured, the interior of which is decorated with ornaments, such, for example, as bread baskets, or the like, since the dirt may be readily removed from such ornamental parts by turning the vessel face downwards. In such a case, as shown at 48 in Fig. 4 a basket so decorated is placed upside down on the respective air-vent-pipe or the standard 47, and then treated as hereinbefore specified, the results obtained being the best imaginable.

It is obvious that in the place of arranging the pipes in a circle, any other arrangement whatsoever may be resorted to; as a rule this will depend upon the shape of the articles to be scoured; for the majority of

cases, however, the annular arrangement will no doubt prove the one most suitable.

The improved arrangement, moreover and at the same time, serves to remove the difficulty which hitherto existed in providing a good support for hollow vessels within the scouring tank. For as will be clear, whatever position was given to them hitherto, whether they were stood upright or placed 10 face downwards in the tank, no sooner was the scouring liquid let in, but they were lifted up and began to float about in the tank. And only after the entire tank was filled with the scouring liquid were they completely immersed therein. Besides, while floating about, the parts frequently rubbed against each other causing their surfaces to be damaged. All this cannot occur when employing the improved scouring tank constructed 20 in accordance with my invention, because in no case are the articles or vessels to be scoured liable to float about in the tank.

In the forms of construction illustrated 25 in Figs. 6 and 7, the system of pipes according to Figs. 4 and 5 is omitted. In the place of this system, there is provided for each hollow vessel 44 requiring to be scoured an approximately U-shaped pipe 50, one 30 limb of which is somewhat longer than the other. The vessel 44 is tilted on the shorter limb, while the longer limb projects beyond the level of the scouring liquid. By these means, the air is free to escape from the said 35 vessel as the scouring liquid enters. The pipes 50 are suspended to crossrods 51, or the like, and they may, to this end be fitted out with hooks or similar contrivances, or they may be even bent so that they may be 40 readily hung up on the said rods 51.

The form of construction shown in Fig. 7 differs from that according to Fig. 6 merely by the fact that the pipes 50 are 45 provided with legs 52, by aid of which they may be set up on the bottom of the scouring-tank.

A further modified form of execution of a 50 device for scouring hollow vessels is disclosed in Fig. 8. In this arrangement, the bottoms 53, on which the metal articles to be scoured are intended to be placed, are adapted to rock about axes 55. The said axes are lodged beyond the centre of the tank so that therefore the said bottoms tend to swing 55 around their axes in the direction denoted by the arrow. The bottoms 53 are preferably provided with recesses or apertures serving to retain the hollow vessels 54 about to be scoured in the proper position. As shown 60 in the drawing, the said articles are laid flat on the bottom. While the tank is as yet empty, the bottoms assume the inclined position marked in full lines in the drawing, their right hand side being now the heavier 65 and therefore sinking downwards. A float

56 is fixed to the heavier side of the bottoms. If now the scouring liquid is caused to flow into the tank through the pipe 7, then, owing to the provision of the float 56, the bottoms begin to turn in a sense counter to that 70 denoted by the arrow and finally come to assume a position in which their left hand section bears down on steps or abutments 57. The bottoms being in this position, the hollow vessels to be scoured will for their part 75 be so disposed as to enable them to fill themselves completely with the scouring-liquid, so that they will contain no intervening spaces filled with air. After the scouring operation has terminated, the scouring liquid 80 is drawn off again; the float will consequently now sink until when the liquid has been entirely drained off the bottoms again assume the positions indicated in full lines 85 and in which the vessels are so disposed as to cause their entire contents to now run out.

While the drawing discloses two bottoms 53, it is obvious that, if preferred, more than two such oscillating bottoms may be arranged, the one above the other; or even 90 only one. Besides, the bottoms may be arranged to be exchangeable, in that, for instance, the axes 54 are adapted to be drawn out, or by the said axes being lodged in bearings open on top, or by similar means, and this for the purpose of being able to use each time bottoms the recesses or openings in which are disposed in conformity with the varying shapes of the hollow vessels to be 95 scoured. The bottoms themselves are preferably made of a material which will not be liable to injure the metal vessels about to be scoured; brass, copper, aluminum will be found to be the metals most suitable for this purpose; in addition, however, the bottoms 100 may be covered with a thin layer of a soft material to act as a protection.

The stops or abutments 57, as also any additional stops 58 which may possibly be provided in order to limit the rotation of the bottoms in the direction denoted by the 110 arrow, may for its part be arranged to be adjustable for the purpose of rendering it possible to regulate the terminal positions of the bottoms in conformity with the shapes 115 of the hollow vessels to be scoured.

A main feature of my invention resides in the fact that—and this is most essential—on completion of the scouring operation all 120 the scouring-liquid is withdrawn from the scouring tank and that thus no residues of scouring liquid or of objectionable gases will enter into the workshop. To this end it is necessary that the bottom, after the scouring operation has terminated, shall assume the position indicated in full lines in the drawing; it is of less importance that the interior of the hollow vessels shall be always 125 completely filled with the scouring liquid since the liquid will always develop vapours 130

which will effect the scouring of any minor parts in the interior of the hollow vessels to which no liquid has penetrated. For this reason there will be secured in certain cases 5 a fairly sufficient scouring even if the final position of the bottom, after the liquid has been filled in, be not at an incline, but, horizontal or, it may be, even slightly inclined in the opposite direction.

10 Where hollow vessels enter into consideration, in the case of which it will not much matter whether the external surface thereof be slightly injured in the scouring or not, i. e. vessels which are subsequently to be 15 either tin coated, japanned, or enameled, then it will be found preferable to employ the more simple arrangement disclosed in Figs. 9 and 10. In the construction here shown, there is arranged a drum 60 in the 20 scouring tank 59, which drum is provided in the known manner with an opening adapted to be closed, and through which the articles or parts to be scoured are inserted. This is 25 preferably done before the drum itself is placed in the tank. After that the drum is shut, the cover 61 of the tank removed, and the drum inserted.

To facilitate this, the tank is provided on 30 one side with a bearing 62, having a slot, into which the drum is fitted by aid of a pin 63. On the opposite side of the tank is arranged a hand wheel or the like, 64, the shaft of 35 which is adapted to engage the shaft 65 of drum 60 by means of a square-headed member, so that by rotating the hand-wheel 64 the drum will be revolved.

After the drum containing the vessels or parts to be scoured has been inserted in the tank, this latter is closed by means of the 40 cover 61, whereupon the duly heated scouring-liquid is pumped into the tank by the pump. Now the drum is set in rotation, the articles or parts in the drum being thereby so jumbled together that even hollow vessels among them will come to be so diversely positioned that every part of their surfaces will be brought in contact with the liquid. The scouring-operation being completed, the 45 scouring-liquid is discharged through the pipe 66 into the collector, the drum continuing to be rotated meanwhile so that all the remains of the liquid which may be still happen to be in any hollow parts or vessels, will be withdrawn therefrom and enabled to run out. It is understood that the drum is 50 constructed in the manner of a sieve or provided with apertures to facilitate the entry and exit of the scouring liquid.

Finally, Figs. 11 to 13 disclose an installation, specially suitable for small works or such where only a limited space is available. In this modified form of execution 67 denotes the scouring-tank, the interior of 55 which may be arranged in any appropriate manner to accommodate the articles to be

scoured. In this case, either the bottom alone, or else the entire tank 67 is double-walled in order to allow of a suitable cooling. The cooling water is admitted at 68 intermediate the double walls of the tank 70 and flows out again at 69. The tank 67 is shown as being arranged stationary on a board, or the like 70. In this construction the collector 71 for the liquid is movably arranged, being, for example, suspended by 75 a rope 72 running across rollers 73, 74 and supporting a counter-weight 80. Below the collector is arranged a heating contrivance 75, which is either stationary or else adapted to be raised and lowered with the collector 71.

Collector and scouring-tank are interconnected by two flexible pipings 76, 79. The pipe 76 terminates in the tank, close to the bottom thereof, whereas at the collector end 85 it terminates somewhat above the bottom of this latter. The closure of this pipe is effected by means of cocks 77, 78; however, in many cases, one such cock may alone be deemed sufficient. The other pipe 79 terminates close to the cover of both receptacles; here, too, there may be provided a cock 90 to effect the closure of said pipe, though this is not absolutely essential for the efficient working of the device. To conclude, the collector 71 is fitted out with a cock 81, for the 90 discharge of deposits.

The manner of operation of the device is as follows: When the scouring operation starts, the tank 67 is empty. Now, the cover 82 thereof is removed and the articles to be scoured are placed in the tank, whereupon the cover is replaced, and, after the cocks 77, 78 have been opened, the collector 71 is raised to such an extent that the scouring-liquid may readily flow from said collector through the pipe 76 into the scouring-tank 67. During this operation, the cock 90 must, of course, be open in order that in the same degree as the liquid passes from the collector 71 into the tank 67, the air will be enabled to escape out of this latter through the pipe 79 into the collector 71. As soon as the scouring operation has terminated the collector 71 is lowered to such an extent again 100 that now the entire liquid will be able to return to it from the tank. Hereupon this latter is cooled in the manner described so that any vapours still present may settle in the form of scouring-liquid; then, say after 105 the cocks 77, 78 have been closed the cover 82 is again removed and the articles scoured are taken out.

The purifying of the scouring-liquid, which has been gradually filled with greasy 125 matter and other impurities, is carried out in the following manner: After the cock 77 has been closed, the collector is raised and the liquid contained therein is boiled. The vapours developed—cock 90 being open— 130

- flow through pipe 79 into the tank 67 into which they are admitted by the intervention of a detachable steam distributing pipe 83, where they finally settle in the shape of the purified liquid. The entire liquid contained in the collector having been evaporated in this way, the residues of oil or other deposits remaining behind are discharged by aid of cock 81.
- 10 The device for raising and lowering the collector 71 may be of any approved kind. In the place of the suspension-arrangement by means of a rope, and as shown in Fig. 11, a contrivance of the kind illustrated by 15 way of example in Fig. 12 may be employed, according to which the collector 71 is fixed to a two-armed lever 84 adapted to rock about an axis 85 lodged in a stationary support 86. The unattached arm of this lever constitutes 20 a handle 87 and in addition supports a counterweight 88 which latter is preferably adjustable and serves to counterbalance the weight of the collector 71.
- By raising or lowering the handle 87, the 25 collector 71 in this construction comes to be raised or lowered in its turn.
- It is obvious, that if deemed more feasible the arrangement may be reversed, and the collector 71 be adapted to be stationary and 30 the tank 67 to be raised and lowered; or else, both these receptacles may be arranged to move by their being mounted as shown, for example, in Fig. 13, on a linked quadrilateral 89 adapted to oscillate on the knife-edges 91. The chief point herein is only 35 that the two receptacles shall be enabled to carry out a lifting and lowering motion relatively to each other and therewith avoid the necessity of arranging a special pump.
- 40 Having now particularly described and ascertained the nature of my invention, what I claim is:
1. A metal scouring and ungreasing device of the type described comprising in 45 combination, a collector adapted to contain the scouring liquid; a closed scouring tank to receive the articles to be scoured; a condenser; means for heating the scouring liquid; means for conducting the liquid from 50 the collector to the scouring tank, and vice versa; a pipe for conducting the vapours existing in the tank to the condenser; and a valve-controlled pipe connecting said condenser and collector.
  - 55 2. A metal scouring and ungreasing device of the type described comprising in combination, a collector adapted to contain the scouring liquid; a closed scouring tank to receive the articles to be scoured; a condenser; means for heating the scouring liquid; means for conducting the liquid from 60 the collector to the scouring tank, and vice versa; means for effecting the distillation of the used scouring liquid; means for conducting the liquid into the still; a pipe for con-
  - ducting the vapours evolved within the still to the condenser; and a pipe connecting said condenser and collector.
  3. A metal scouring and ungreasing device of the type described comprising in 70 combination, a collector adapted to contain the scouring liquid; a closed scouring tank to receive the articles to be scoured; means for heating the scouring liquid; a condenser; a still; means for alternately conducting the 75 scouring liquid from the collector into the scouring tank and the still; a pipe for conducting the vapours evolved within the still to the condenser; and a pipe connecting said condenser and collector. 80
  4. In a metal scouring and ungreasing device of the type described, a closed scouring tank receiving the articles to be scoured; an inlet and an outlet for the scouring liquid; and cooling means suitable to be put 85 into action after the scouring liquid has been drawn off in order to effect condensation of any vapours rising from the scouring tank which have been developed by the evaporation of the liquid-particles adhering 90 to the hot scouring tank and hot surfaces of the scoured articles.
  5. A metal scouring and ungreasing device of the type described comprising in 95 combination, a closed scouring tank for receiving the articles to be scoured; an inlet and an outlet for the scouring liquid; and cooling means adapted to cool a part of the scouring tank after the scouring liquid has 100 been drawn off in order to produce a condensation of any vapours rising from the scouring tank which have been developed by the evaporation of the liquid particles adhering to the hot scouring tank and hot surfaces of the scoured articles. 105
  6. In a metal scouring and ungreasing device of the type described, a closed scouring tank having a space adapted to receive the articles to be scoured, and a lower discharge space for the scouring-liquid. 110
  7. In a metal scouring and ungreasing device of the type described, a closed scouring tank having a space adapted to receive the articles to be scoured, and a lower discharge space for the scouring liquid; and a 115 foraminous shelf for separating the discharge space from the article receiving space.
  8. In a metal scouring and ungreasing device of the type described, a closed scouring tank having a space adapted to receive the articles to be scoured and a lower discharge space for the scouring liquid; a foraminous shelf for separating said spaces; and means for introducing the scouring liquid into the 120 said lower space.
  9. In a metal scouring and ungreasing device of the type described, a closed scouring tank having a space adapted to receive the articles to be scoured and a lower discharge 125 space.

space for the scouring liquid; and means for introducing the scouring liquid into the said lower space in a tangential direction.

10. A metal scouring and ungreasing device of the type described comprising in combination a closed scouring tank adapted to receive the articles to be scoured; an inlet and an outlet for the scouring liquid; a collector; means whereby the scouring liquid may continue to flow from the collector into the tank during the whole scouring operation; and an overflow pipe provided near the upper end of the tank through which the excess liquid flows continuously back into the collector.

11. A metal scouring and ungreasing device of the type described comprising in combination, a collector adapted to contain the scouring liquid; a closed scouring tank to receive the articles to be scoured; a heating apparatus adapted to heat the scouring liquid within the collector; means for permitting the hot scouring liquid to continue to flow from the collector into the tank during the whole scouring operation; and an overflow pipe provided near the upper end of the tank through which the excess liquid is continuously led back to the collector.

12. A metal scouring and ungreasing device of the type described comprising in combination, a collector adapted to contain the scouring liquid; a closed scouring tank having an upper space for accommodating the articles to be scoured and a lower discharge space for the scouring liquid; a heating apparatus to heat the scouring liquid within the collector; and means for introducing the hot scouring liquid into the said lower space in a tangential direction.

13. A metal scouring and ungreasing device of the type described, comprising in combination, a collector adapted to contain the scouring liquid; a closed scouring tank to receive the articles to be scoured; means for heating the scouring liquid within the collector; means for conducting the hot scouring liquid from the collector to the scouring tank and vice versa; and cooling means adapted to cool a part of the scouring tank after the scouring liquid has been drawn off in order to effect a condensation of any vapours rising from the scouring tank which have been developed by the evaporation of the liquid particles adhering to the hot scouring tank and hot surfaces of the scoured articles.

14. A metal scouring and ungreasing device of the type described comprising in combination, a closed scouring tank having an inlet and an outlet for the scouring liquid; a frame disposed within the tank and adapted to support the articles to be scoured, said frame being arranged movable rela-

tively to the scouring tank and scouring liquid within the tank and cooling means adapted to cool a part of the scouring tank after the scouring liquid has been drawn off in order to effect a condensation of any vapours rising from the scouring tank which have been developed by the evaporation of the liquid particles adhering to the hot scouring tank and hot surfaces of the scoured articles.

15. A metal scouring and ungreasing device of the type described comprising in combination, a closed scouring tank having an inlet and an outlet for the scouring liquid; a frame disposed within the tank and adapted to support the articles to be scoured, said frame being arranged so as to rotate about its axis and cooling means adapted to cool a part of the scouring tank after the scouring liquid has been drawn off in order to effect a condensation of any vapours rising from the scouring tank which have been developed by the evaporation of the liquid particles adhering to the hot scouring tank and hot surfaces of the scoured articles.

16. A metal scouring and ungreasing device of the type described comprising in combination, a closed scouring tank having an inlet and an outlet for the scouring liquid; a frame disposed within the tank and adapted to support platforms of foraminous material adapted to contain the articles to be secured, said frame being arranged movable relatively to the scouring tank and scouring liquid within the tank and cooling means adapted to cool a part of the scouring tank after the scouring liquid has been drawn off in order to effect a condensation of any vapours rising from the scouring tank which have been developed by the evaporation of the liquid particles adhering to the hot scouring tank and hot surfaces of the scoured articles.

17. A metal scouring and ungreasing device of the type described comprising in combination, a closed scouring tank having an inlet and an outlet for the scouring liquid; a drum adapted to receive hollow articles to be scoured, to be inserted in the scouring tank; means for rotating the drum while the scouring liquid flows into the scouring tank and after the latter has been drawn off and cooling means adapted to cool a part of the scouring tank after the scouring liquid has been drawn off in order to effect a condensation of any vapours rising from the scouring tank which have been developed by the evaporation of the liquid particles adhering to the hot scouring tank and hot surfaces of the scoured articles.

In testimony whereof I have affixed my signature.

MAX HELLER.
